STRAIGHTENING DEVICE

Filed June 14, 1926

UNITED STATES PATENT OFFICE

ALBERT RAUSCH, OF DETROIT, MICHIGAN, ASSIGNOR TO AMERICAN TWIST DRILL
AND TOOL COMPANY, OF DETROIT, MICHIGAN, A CORPORATION OF MICHIGAN

STRAIGHTENING DEVICE

Application filed June 14, 1926. Serial No. 115,815.

The present invention relates to straightening devices and particularly to devices for straightening short metal articles or pieces, such, for example, as drills and the like.

Among the objects of the invention is a device of the kind indicated which is economical to make and easy to adjust and operate.

Another object is a device of the kind which can be operated more rapidly and efficiently than with devices now used for the purpose.

Still other objects will readily appear to those skilled in the art upon reference to the following description and drawings in which:—

Fig. 1 is a plan view of the device.

Fig. 2 is section thereof on line 2—2 of Fig. 1.

Fig. 3 is a side view of the base plate.

As indicated in the drawings, the device comprises a bed plate 10 having a guideway 11 in which are adapted to slide three jaw carrying members 12, 13, and 14 having the jaws 15 and 16. These members 12, 13, and 14 are longitudinally bored and threaded for the reception of connecting and adjusting pins 17 which latter are provided at one end with ball sockets 18 and at the other end with slots 19 by means of which the pins may be turned to move the members 12, 13, and 14 thereon.

The ball sockets 18 cooperate with balls 20 forming one end of connecting rods 21, connecting the pins 17 to a crank-shaft 25 and the three throws of the latter are arranged in one plane with the center one opposite the other two so that revolution of the shaft moves the one jaw carrying member 13 in an opposite direction to that of members 12 and 14.

This crank-shaft is mounted in one end of the bed plate and provided with four bearings which are at 26, 27, 28, and 29. It is preferred to form the bed plate 10, as indicated in Figs. 1 and 3 with integral upstanding side walls 30 and intermediate bearing supports 27 and 28, so as to maintain the shaft against bending when being

used for a straightening operation. Means, such as a hand lever 31 will be attached to the extended end of shaft 25 for turning the latter.

As indicated in Fig. 1, that portion of bed plate 10 having the guideway 11 is provided with a cover plate 40 having therein slots 41 through which project the jaws 15 and 16 and these slots and jaws are so arranged that the two outer ones lie on one side and the inner one on the other side of an imaginary intermediate line across the device. It will also be noted that the jaws 15 are opposed to the jaw 16.

Opposite the space between the jaws and located on the imaginary line are two holders for the work piece to be straightened. One of these holders consists of a barrel 45 secured to one side of plate 10, having a spring pressed plunger 46 passing therethrough. The inner end of the plunger is provided with a suitably formed end 47 adapted to hold one end of the work piece, while the outer end of the plunger 46 is provided with a suitable grip piece 48. The other holder consists of a block 50, having a suitably shaped jaw piece 51 in alignment with and opposed to plunger end 47, which block is slidably mounted on a bracket 52 secured to the other side of plate 10 and fixed in adjusted position by means of a suitable screw 53. These two holders support the work between the jaws 15 and 16 while the latter are being moved toward or away from the work. Of course it is understood that when the jaws 15 and 16 have gripped the work piece no other support is necessary. The holders are therefore chiefly centering devices.

Having now described the invention and the preferred form of embodiment thereof it should be understood that the said invention is not to be limited to the specific details herein set forth but only by the scope of the claims which follow.

I claim:—

1. A straightening device comprising a bed plate, a multiple throw crank-shaft mounted at one end thereof three jaw carrying members in a guideway in the other

end thereof and adapted to be reciprocated by said shaft, the shaft being arranged to move some of the members in one direction and the others simultaneously in the opposite direction and means independent of said members and shaft for supporting the work between said jaws.

2. A straightening device having a bed plate provided with a guideway, a top plate 10 provided with parallel slots located over said guideway, members slidable in said guideway and having jaws extending through said slots, said slots and jaws arranged with alternate jaws on either side of an intermediate line, means to support a work piece 15 between said jaws and with its axis parallel to and above said line and means to cause all of said jaws simultaneously to approach or recede from said line to thereby grip and 20 bend said work piece.

3. A straightening device having a bed plate provided with a guideway, a top plate provided with parallel slots located over said guideway, members slidable in said guideway and having jaws extending through said slots, said slots, and jaws arranged with alternate jaws on either side of an intermediate line, means to adjust the position of a jaw with reference to said line, means to 25 support a work piece between said jaws and with its axis parallel to and above said line and means to cause all of said jaws simultaneously to approach or recede from said line to thereby grip and bend said work piece.

35 ALBERT RAUSCH.
